UNITED STATES PATENT OFFICE.

LUTHER P. TURNER AND JOHN R. BURRILL, OF SPOKANE, WASHINGTON.

ROADWAY.

1,338,801.

Specification of Letters Patent. Patented May 4, 1920.

Application filed October 13, 1919. Serial No. 330,216.

To all whom it may concern:

Be it known that we, LUTHER P. TURNER and JOHN R. BURRILL, citizens of the United States, residing at Spokane, in the county 5 of Spokane, State of Washington, have invented a new and useful Roadway, of which the following is a specification.

This invention relates to roadway construction, and the primary object of the invention is to provide a combination concrete or reinforced concrete and gravel earth, or 10 other material roadway, wherein the concrete is formed into blocks or strips.

A further object of the invention is to 15 provide means for permitting the blocks or strips of concrete to expand and contract, with relation to each other, without disrupting the road surface.

A further object of the invention is to 20 provide means for connecting the coöperating ends of adjacent blocks, whereby the blocks may be readily and efficiently connected, to restrict longitudinal and lateral movement of one member, with relation to 25 the other.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention. 35

Referring to the drawings:—

Figure 1 illustrates a fragmental view of a roadway constructed in accordance with 40 the present invention.

Fig. 2 is a fragmental side elevational view of the adjacent ends of the concrete blocks.

Fig. 3 is a sectional view taken on line 3—3 of Fig. 2.

Fig. 4 is a plan view illustrating a modified form of means for connecting adjacent ends of concrete blocks, and

Fig. 5 is a fragmental side elevational view of the other modified form of end securing means.

Referring to the drawing in detail, the reference character 5 designates the concrete blocks, employed in the construction

of a roadway, according to the present invention, and as shown, these blocks 5, are 55 arranged in spaced relation with each other, and disposed in parallel relation with the sides of the roadway.

In one form of construction, the blocks are provided with the parallel rods 6, embedded in one of the ends thereof, the rods 6 having portions 7 extending beyond the end wall of the block to which the same are secured, which extended portions 7 are designed to be positioned within the openings 8, formed in the end of the adjacent block, the diameter of the openings being equal to the diameter of the rods 6, so that the rods 6 will be securely housed therein, to prevent lateral displacement of one block 70 with relation to the other; said socket 8 may or may not be metal lined and may extend into the block for reinforcing.

In constructing a roadway in accordance with Fig. 2 of the drawings, the adjacent ends of the blocks, are positioned in spaced relation with each other, which space, accommodates the transversely extending bolt 9, which bolt is provided with the usual head 10, formed on one end 80 thereof, and a threaded nut 11, on the opposite end thereof, the nut 11, being adapted to move into engagement with the plate 12, for clamping the plates 12 and 13, to the adjacent ends of the blocks.

Each of these plates 12 and 13, is substantially long, and provided with an integral flange 14, which flange is adapted to lie within the space between the adjacent ends of blocks, to prevent movement of the plates 90 with relation to the blocks, and as shown, each of these plates is provided with a central opening indicated at 15, which openings, of coöperating plates, receive the transversely extending bolt 9, which bolt, 95 when properly positioned with relation to the blocks, clamps the plates 12 and 13 to the sides of the blocks.

In the form of the invention as illustrated by Figs. 4 and 5 of the drawings, one 100 end of one of the blocks is shown as provided with the usual rods 6, the adjacent end of the opposed block being shown as provided with an elongated cut out portion 6' to receive the extended ends of the rods 6. 105

This construction has been found in prac-

tice to be one which may be readily assembled, since the extended ends of the rods 6, 5 may be moved into engagement with the side walls of the cut out portion without the necessity of guiding the same thereto, as in the structure disclosed by Fig. 4 of the drawing.

With reference to Fig. 1 of the drawing, the roadway includes the blocks 5 which, as 10 before stated, are supported in spaced relation with each other, the portions between the blocks being filled in with gravel, and topped with cement or other similar road dressings.

15 The construction as illustrated, restricts lateral, as well as longitudinal movement of the concrete blocks with relation to each other, and insures against the blocks, or ends thereof moving with relation to each other, 20 to disrupt or otherwise render the roadway objectionable.

It might be further stated that these 25 spaces between the adjacent ends of blocks, are filled with properly formed paper filler strips 16 which permit of a slight longitudinal movement between the adjacent blocks, and at the same time maintain the space between the blocks as closed.

Having thus described the invention, what is claimed is:—

30

1. In a roadway construction, spaced parallel longitudinal blocks, the adjacent ends of the blocks being supported in spaced relation with each other, a bolt disposed within the space, plates supported on the 35 bolt, and adapted to clamp opposite faces of adjacent blocks, and a filling material between the adjacent ends of the blocks.

2. In a roadway construction, spaced parallel longitudinal blocks, the adjacent ends 40 of the blocks being supported in spaced relation with each other, a bolt positioned within the space, plates supported on the bolt, each of said plates having flanges positioned between the ends of the blocks, said 45 plates adapted to clamp opposite faces of adjacent blocks, and a filling material between the adjacent ends of the blocks.

In testimony that we claim the foregoing as our own, we have hereto affixed our signatures in the presence of two witnesses.

50
LUTHER P. TURNER.

JOHN R. BURRILL.
